DOLL EYE BULB

Filed April 11, 1930

INVENTOR.

Samuel Heilweil

BY *Julian A. Polachek*
ATTORNEY

UNITED STATES PATENT OFFICE

SAMUEL HEILWEIL, OF NEW YORK, N. Y., ASSIGNOR OF ONE-HALF TO ABRAHAM MESSER AND ONE-HALF TO ROBERT B. MESSER, BOTH OF BROOKLYN, NEW YORK

DOLL EYE-BULB

Application filed April 11, 1930. Serial No. 443,310.

This invention relates to new and useful improvements in an eye mechanism for a doll's head.

The invention has for an object the provision of a device of the class mentioned which is of simple durable construction, dependable in use and efficient in action, and which can be manufactured and sold at a reasonable cost.

10 The invention proposes in combination with a doll's head having openings at the eyes, eye ball members within the doll's head and behind said openings and consisting of electric bulbs with translucent eye-forming members upon their fronts, sockets supporting said electric bulbs, a bracket supporting said sockets and pivotally mounted at its top end, a contact finger depending from said bracket and engageable with a 15 stationary contact, an electric circuit including said lamps and contacts, and adjustable means for changing the center of gravity of said bracket and parts thereon for gravity control of said contact finger to 20 close the circuit at desired positions of said doll's head.

For further comprehension of the invention, and of the objects and advantages thereof, reference will be had to the following description and accompanying drawings, and to the appended claims in which the various novel features of the invention are more particularly set forth.

In the accompanying drawings forming 35 a material part of this disclosure:—

Fig. 1 is a perspective view of a doll's head with an eye mechanism constructed according to this invention.

Fig. 2 is a vertical sectional view taken 40 on the line 2—2 of Fig. 1.

Fig. 3 is a front elevational view of the eye mechanism shown in Fig. 2, per se.

Fig. 4 is a side elevational view of one 45 of the bulbs per se, used in the eye mechanism.

Fig. 5 is a fragmentary enlarged sectional view of the bulb shown in Fig. 4.

The reference numeral 10 indicates generally a doll's head of any conventional design and construction, having standard fea-

tures such as a mouth 11, a nose 12, hair 13 and eyes 14. This doll's head is hollow as may be seen from an inspection of Fig. 2 and is provided with a removable rear section indicated by reference numeral 10'. 55

The eye mechanism for the doll's head consists of eye ball members 15 within the doll's head and behind openings 16 formed in the doll's head in the vicinity of the eyes and consisting of electric bulbs 17 with translucent eye-forming members 18 on their fronts, sockets 19 supporting said electric bulbs 17, a bracket 20 supporting said sockets 19 and pivotally mounted at its top end 21, a contact finger 22 depending from said bracket 20 and engageable with a stationary contact 23, an electric circuit including said lamps 17 and the contacts 22 and 23, and adjustable means for changing the center of gravity of said bracket 20 and the parts 60 thereon for gravity control of said contact finger 22 to close the circuit at desired positions of the doll's head. The bracket 20 has suitable extensions to form eye lids 20'. 65

The openings 16 in the doll's head are 70 slightly smaller than the fronts of the bulbs 17 so that the bulbs may engage behind the openings. The sockets 19 are of conventional type, that is, they consist merely of a shell formed with screw threads. The bracket 20 75 constitutes a flat member which has its top end 21 turned around upon a horizontal rod 24 for constituting the pivotal mounting thereof. The rod 24 is supported upon lugs 25 projecting from a partition 26 removably 80 mounted within the doll's head. This partition is slidably connected on lugs 27 which are secured to the doll's head by screws 28 for accomplishing the removable mounting. 85 Tension springs 27' force the partition 26 against head 27^a of lug 27. The electric bulb 17 may be changed when it is burnt out by pulling the partition 26 against the tension of spring 27'. The contact finger 22 is insulated from the bracket 21 by insulation washers 29 and acts merely against the rear contacts of the electric bulbs 17 for completing an electrical connection from the sockets 19 thru the filaments of the bulb and to the 90 95 100

said contact finger 22. The stationary contact 23 is mounted upon the partition 26.

The electric circuit before referred to includes a battery 30 supported by a clip 31 upon the partition 26 and formed with a top terminal 32 in electrical contact with the stationary contact 23. Leads 33 connect with the casing terminal of the battery 30 and with the sockets 19, thru a switch 33' located at any suitable location in the body of the doll.

These leads are formed with a plurality of coiled portions 34 so as to permit swinging of the bracket 20 upon its pivotal mounting. The circuit continues from the end contacts 15 of the lamps to the contact finger 22 and in certain positions of the head to the stationary contact 23 and thus back to the battery.

The said adjustable means for changing the center of gravity of said brackets and parts thereon comprises a screw 35 rotatively supported on the contact finger 22 and threadedly engaging a weight 36 slidably arranged upon a horizontal bottom portion 37 of the contact finger so as to be slidable. A sprocket wheel 38 is fixed upon the screw 35 and connects with a chain 39 connecting with another sprocket 40 fixed upon a spindle 41 rotatively mounted upon the bracket 20 near the top end 21. This spindle passes thru an aperture 42 in the partition 26 and terminates in an opening 43 in the doll's head so as to be reachable upon separating of the hair 13 of the doll's head. This extended end of the spindle is formed with a head portion for engagement by a turning tool.

The electric bulbs 17 are of conventional design except that their glass casings 44 are formed with depressed fronts 45 so as to receive the said translucent eye-forming members 18, and the casing member may be painted to resemble eye lids when the electric bulb is used in a sleeping doll. These members are preferably of celluloid, suitably painted and cemented on in place. Celluloid is chosen since it is translucent and allows the passage of light.

In operation of the device, when the doll's head is tilted the bracket 20 and the parts mounted thereon moves so that in certain positions of the head, contact is made between the finger 22 and the stationary contact 23 for closing the electrical circuit and causing the lighting of the lamps 17. Thus the eyes of the doll become illuminated. If it is desired to make an adjustment so that the eyes of the doll become illuminated at a different inclined position, it is merely necessary to turn the spindle 41 for transmitting rotations to the screw 35 so as to move the weight 36 along upon the horizontal portion 37 of the contact finger 22 to change the center of gravity of the bracket and the parts connected therewith.

It is to be understood that my electric eye bulb may be used in the heads of any toy or

display figure even of the non-sleeping type, and the bulb may be inserted in its socket by threads, bayonet slot connection or by friction as desired.

This arrangement may also be used by connecting the bulbs 17 to the usual 110 volt circuit.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. In combination with a doll's head, having openings at the eyes, eyeball members within the doll's head and behind said openings and consisting of electric bulbs with translucent eye-forming members on their fronts, sockets supporting said electric bulbs, a bracket supporting said sockets and pivotally mounted at its top end, a contact finger depending from said bracket and engageable with a stationary contact, an electric circuit including said lamps and contacts, and adjustable means for changing the center of gravity of said bracket and parts thereon for gravity control of said contact finger to close the circuit at desired positions of said doll's head.

2. In combination with a doll's head, having openings at the eyes, eyeball members within the doll's head and behind said openings and consisting of electric bulbs with translucent eye-forming members on their fronts, sockets supporting said electric bulbs, a bracket supporting said sockets and pivotally mounted at its top end, a contact finger depending from said bracket and engageable with a stationary contact, an electric circuit including said lamps and contacts, and adjustable means for changing the center of gravity of said bracket and parts thereon for gravity control of said contact finger to close the circuit at desired positions of said doll's head, said bracket constituting a flat member with a turned top end engaged upon a horizontal rod supported within the doll's head.

3. In combination with a doll's head, having openings at the eyes, eyeball members within the doll's head and behind said openings and consisting of electric bulbs with translucent eye-forming members on their fronts, sockets supporting said electric bulbs, a bracket supporting said sockets and pivotally mounted at its top end, a contact finger depending from said bracket and engageable with a stationary contact, an electric circuit including said lamps and contacts, and adjustable means for changing the center of gravity of said bracket and parts thereon for gravity control of said contact finger to close the circuit at desired positions of said doll's head.

gravity control of said contact finger to close the circuit at desired positions of said doll's head, said bracket constituting a flat member with a turned top end engaged upon a horizontal rod supported within the doll's head, a partition being removably mounted within the doll's head and carrying supporting lugs supporting said horizontal rod.

5. In combination with a doll's head, having openings at the eyes, eyeball members within the doll's head and behind said openings and consisting of electric bulbs with translucent eye-forming members on their fronts, sockets supporting said electric bulbs, a bracket supporting said sockets and pivotally mounted at its top end, a contact finger depending from said bracket and engageable with a stationary contact, an electric circuit including said lamps and contacts, and adjustable means for changing the center of gravity of said bracket and parts thereon for gravity control of said contact finger to close the circuit at desired positions of said doll's head, said contact finger being insulated from said bracket.

25. In combination with a doll's head, having openings at the eyes, eyeball members within the doll's head and behind said openings and consisting of electric bulbs with translucent eye-forming members on their fronts, sockets supporting said electric bulbs, a bracket supporting said sockets and pivotally mounted at its top end, a contact finger depending from said bracket and engageable with a stationary contact, an electric circuit including said lamps and contacts, and adjustable means for changing the center of gravity of said bracket and parts thereon for gravity control of said contact finger to close the circuit at desired positions of said doll's head, comprising a screw rotatively mounted on said contact finger and threadedly engaging a weight slidably arranged on the horizontal portion of the contact finger, and means for adjusting the rotative position of said screw reachable from the exterior of the doll's head.

In testimony whereof I have affixed my signature.

50 SAMUEL HEILWEIL.
